DEVICE FOR SEPARATING FLAT OBJECTS ACCORDING TO THEIR LINEAR DIMENSIONS

Jean-Paul Moricet, Sevres, France, assignor to Compagnie Generale d'Automatisme, Paris, France, a corporation of France

Filed Oct. 27, 1964, Ser. No. 406,745
 Claims priority, application France, Nov. 12, 1963,
 953,379

20 Claims. (Cl. 209—84)

This invention relates more particularly to a device, which is part of an equipment such as, for instance, one of the type of that called "segregator," the aim of which is to make automatically, out of sets of flat objects such as the content of postal bags, piles of objects, such as envelopes, having uniform dimensions, in order to allow the carrying out of the classifying operations by high capacity machines. Among the operations which are necessary for this purpose, there is the separation according to the rectangular dimensions of the postal envelopes or of the flat objects of a set.

The object of this invention is more particularly a machine which classifies into two batches the envelopes arriving individually: the envelopes for which the rectangular dimensions are lower than a critical length, or separation modulus m , and the envelopes for which the rectangular dimensions are larger than the modulus m .

The object of the invention is a separation process for flat objects such as postal envelopes or the like according to their dimensions, particularly remarkable in that the objects are classified by passing them through an arrangement of fingers in the manner of the pegs of a rake or the like. Advantageously, the objects are guided between surfaces which are approximately vertical or slightly slanting, possibly splayed out towards the top, and the fingers are moving, this movement being preferably a uniform translation.

Another object of the invention is a device for implementing the above-mentioned process, particularly remarkable in that it comprises two flat channel sections in prolongation one of the other, together with classifying means located between them, the small objects passing through both sections while the large objects are carried laterally by said means. Preferably, the upper channel is splayed towards the top and is shaped as a spout. In an advantageous embodiment of the invention, the above-mentioned segregating means are made up of a finger arrangement, forming the pegs of a rake or the like, which may move along a direction approximately crosswise to the above-mentioned channel, and preferably substantially perpendicular to the plane of said channel.

According to the invention, a machine for classifying flat objects with reference to a modulus m comprises essentially, on a stand, the following members:

A first spout or channel section, having a V shape, with approximately a vertical plane of symmetry, opened by a slot, at the bottom, on all its length.

Close below the slot of the above-mentioned spout, an arrangement for dimensional classification formed by a line of horizontal fingers, perpendicular to the slot, spaced from side to side by a distance m and fastened to a moving flexible endless band, which imparts to said fingers a translation motion along the slot of the first spout.

Below the lower side of the above-mentioned fingers, a second spout, made up with two vertical surfaces and opened at top and bottom.

Below the above-mentioned second spout, an endless conveyor band.

A first transfer station for the envelopes, the dimensions of which are smaller than the distance m and which are called small envelopes.

2

A second transfer station for the envelopes, the dimensions of which are larger than the distance m , and which are called large envelopes.

The envelopes individually dropped into the top of the V-shaped spout, at one of its ends, arrive at the slot standing on their edge. The small envelopes fall between two adjacent fingers, pass between the walls of the second spout, their edge rests on the conveyor band, which carries them towards the first transfer station. The large envelopes are held trapped between two adjacent fingers and are carried by the moving fingers to the second transfer station. The critical length m , which is the segregation basis can be adjusted by multiple integers of a unit length, or pitch.

15 The various components of the machine will be described with reference to the accompanying drawings which show a nonlimitative example of embodiment of the machine.

20 FIGURE 1 is an isometric view of the whole of the machine;

FIGURE 2 is a section along the plane AA';

FIGURE 3 shows the fastening of a finger;

FIGURES 4, 5 and 6 are design details relevant to the transfer of the large envelopes.

25 In FIGURE 1, the V-shaped spout 1 is made up of two side plates 1a, 1b and comprises a terminal part 1c, which receives the envelopes to be classified with regard to their dimensions. The fingers, such as 2, are carried by the endless band 2a, which is held by the wheels 2b, 2c. The driving wheel 2b is driven, via the shaft 2d, by the motor unit 3 and the pulley 4. One of the side plates 5a of the second spout 5 can be seen. A conveyor band 6 is driven via roller 6c by said pulley 4. The wheel 2b rotating as shown by the arrow f₁, and the roller 6c by the arrow f₂, the fingers 2 which move between the two spouts, and the upper side 6a moving below the second spout, all have velocities in the same direction.

30 A small envelope such as 7a falls to the bottom of the second spout. Another, 7b, previously introduced, arrives near the end of said spout, where is provided the first transfer station mentioned above, constituted by a mere open box 8. Another small envelope 7c is shown as it is being poured into the transfer station 8.

35 The second transfer station is shown in 10, it is driven by the motor 11. A large envelope 9a, trapped between a pair of fingers can be seen. Another one, 9b, is being transferred by the second transfer station 10. The third large envelope is shown at the outlet of the second transfer station 10. The third large envelope is shown at the outlet of the second transfer station 10. The large envelope transfer station 10 will be described hereunder with reference to FIGURES 4, 5 and 6.

40 In the sectional view of FIGURE 2, 1a and 1b are the two sides of the V-shaped spout, 1d is the bottom slot of said V-shaped spout; 5a and 5b are the two sides of the second spout; 2 is a finger fastened onto the flexible band 2a; 6a and 6b are the two sides of the conveyor band 6. A small envelope 7a is shown resting on its edge on the upper side 6a of the conveyor band 6 and a large envelope 9a is shown resting on the finger 2.

45 FIGURE 2 shows at the upper edge of the V-shaped spout an eccentric winch 12. The function of this member is as follows: the comprehensive equipment for segregation according to linear dimensions comprises, on principle, not only one machine but a plurality of machines set side by side. It may happen, under these conditions, that, when pouring the envelopes into the upper part of the V-shaped spouts, some of the envelopes remain in equilibrium on the two adjacent edges of two neighbouring V-shaped spouts. An eccentric winch such as shown in 12 of FIGURE 2 will then hit such an envelope and make it fall into either one of the two neighbouring

V-shaped spouts. A number of such eccentric winches are installed in the loading areas of the V-shaped spouts, that is, along raised parts such as 1c.

FIGURE 3 shows on a larger scale a sectional view of the conveyor band 2a fitted with a finger 2. This band, of trapeziform section, slides into a lower wooden spout 2c, which has a section adequate for housing said band and is restrained at the top by the wooden batten 2f. In this way, the conveyor band cannot sag under the weight of the envelopes resting on the fingers.

FIGURE 3 also shows a finger 2 comprising a head 2g and a thinner end 2h, which penetrates a plain hole provided in the band 2a. On the back side of the conveyor band 2, the end of this finger is held by an elastic snapping 2j pushed into the groove 2k. Mounting the fingers is hence an easy task.

The band is provided with holes, the axes of which are separated by a relatively small distance, or pitch, for example $p=20$ mm. The above-mentioned segregation modulus is adjusted by letting a certain number n of holes non-used between two holes fitted with successive fingers. Letting d be the diameter of the fingers, the segregation modulus m is given by the relation:

$$m = (n+1)p - d$$

It is hence easy to vary it by an integer of the pitch p .

FIGURE 4 shows an isometric view of the large envelope transfer station seen from the opposite side as compared to FIGURE 1. It comprises an endless conveyor band 101 with vertical translation driven by a motor 102 via a belt 103 and a roller 104 with an axis 105, which is held by two channels 106 mounted on the machine stand. FIGURE 4 shows only the upper part of the channels. At the level of the roller 104, several endless belts rub against the upper part of the band 101, while one of the two strands bears on its full length upon the band 101. Three of these endless belts 107, 108, 109 are shown on FIGURE 4: they go around the same upper spindle 110, which is carried by said channels 106. The distance between the axes 105 and 110, determined by drillings into the channels 106, ensures the required rubbing force magnitude so as to enable the transfer station to operate under the best conditions. The lower parts of the belts go around individual pulleys 111, 112, 113. Each of these pulleys is held in a fork, three forks 114, 115, 116 being shown, the first two being shown only partially for clarity purposes. The fork 116 is pushed by compression of the spring 117, resting on the thrust plate 118 attached to the stand of the machines, towards the conveyor band 101. The belt 109 is thus held in contact with the band 101 on the full length of the strand facing said band. The pressure exerted by the belt 109 upon the band 101 can be adjusted by setting the position of the thrust plate 118 by means not shown.

The other forks 114, 115 are similarly mounted. It hence results that the three belts 107, 108, 109 are all held in contact with the band 101 with a force which can be set for each individual belt. Being of round section, they have a better adherence than if they were rectangular in section, since they flatten out more easily.

FIGURE 6 is an end view of the whole arrangement. The numbers designate the same items as in FIGURES 3 and 4 respectively. The arrows shown in the figure help understand the kinematic relationship between the moving parts.

FIGURE 5 is an elevation of the transfer arrangement. It is a schematic view. The lengths of the belts 107, 108, 109 are selected so that the axis of the lower pulleys be aligned on a line making a 45° angle with the horizontal. This 45° value was preferentially selected since it is the statistically most probable angle value which the side of an envelope 9b makes when it reaches the transfer station.

Should the envelope be caught in one point only by rubbing between a belt such as, for instance, the belt 107, and the belt 101, it might rotate around this point, and

this would impair the satisfactory operation of the transfer station. With the selected arrangement, the envelopes will be caught simultaneously in several points and will be raised smoothly, trapped between the band 101 and the belts 107, 108, 109.

Obviously, the number of belts needs not be 3 and their lengths might be selected according to other criteria without outgoing the scope of the invention.

What I claim is:

- 10 1. An apparatus for sorting objects according to their dimensions, comprising:
a first vertically extending channel formed by two walls and open at both the top and the bottom,
a movable sieve arranged beneath the bottom opening of said channel and along its length, operable to let the small objects pass through and to carry the bigger objects from one end to the other end of said channel,
and means associated with said other end for gripping and vertically evacuating the objects carried by said sieve, said means comprising vertical conveyor means and means cooperating with said vertical conveyor means for applying said objects against the gripping surface of said conveyor means.
- 15 2. An apparatus according to claim 1, wherein said sieve comprises a series of parallel, regularly spaced fingers substantially perpendicular to the lateral walls of said first channel, said fingers being secured to a movable member placed outside and laterally driven along said channel.
- 20 3. An apparatus according to claim 2, wherein said movable member is a flexible belt cooperating with pulley means having the axis of rotation perpendicular to the horizontal plane.
- 35 4. An apparatus according to claim 3, wherein said belt comprises a series of regularly spaced holes, said fingers being fitted into a plurality of holes of said series.
- 40 5. An apparatus according to claim 4, wherein the portion of the fingers fitted into the holes of the flexible belt has a reduced diameter, extended through said belt, and comprises a transversal groove into which a snap ring is inserted for fastening said finger.
- 45 6. An apparatus according to claim 3, comprising guide means for supporting and guiding said flexible belt along said first channel.
- 50 7. An apparatus according to claim 6, comprising a first elongated member having a groove in which a lower part of the flexible belt slidably engages and a second elongated member placed in sliding contact with an upper part of said flexible belt for maintaining the engagement thereof with said first member.
- 55 8. An apparatus according to claim 7, wherein said first and second members are made of wood.
9. An apparatus according to claim 2, comprising a horizontal conveyor belt situated beneath and along the length of said sieve and operable to evacuate the objects which have passed through said sieve.
- 60 10. An apparatus according to claim 2, comprising a horizontal conveyor belt, situated beneath and along the length of said sieve and operable to evacuate the objects which have passed through the sieve, in the same direction as the direction of the movement of said sieve.
- 65 11. An apparatus according to claim 10, comprising driving means for driving said sieve and said horizontal conveyor at equal speeds.
- 70 12. An apparatus according to claim 10, comprising a second vertically extending channel open at both top and bottom, having substantially the same width as said first channel, said second channel being placed between the sieve and the horizontal conveyor so as to guide the objects passing through the sieve.
- 75 13. An apparatus according to claim 2, comprising means for feeding the objects to be sorted and means for guiding said objects into said first channel.
14. An apparatus according to claim 1, wherein said

vertical conveyor means is an endless conveyor belt and said means for applying the objects comprises at least two vertical endless bands having different lengths and mounted respectively on two pairs of pulleys, a first pulley of each pair being rotatably mounted on a fixed horizontal shaft, a second pulley of each pair being rotatably mounted on a horizontal movable shaft, means for tightening said vertical bands and means for urging the surface of said vertical bands against the surface of the vertical conveyor belt.

15. The apparatus according to claim 14, wherein said means for tightening the vertical bands and for urging the latter against the vertical conveyor belt comprise fork-shaped supports holding an individual shaft for each second pulley of each pair, and spring means mechanically connecting each of said supports to a fixed portion of the apparatus.

16. The apparatus according to claim 14, wherein said vertical bands have a substantially round cross section.

17. The apparatus according to claim 14, wherein the centers of said second pulleys of each pair are aligned along a straight line making an angle of 45° with the horizontal direction.

18. The apparatus according to claim 3, comprising:
a horizontal conveyor belt situated beneath and along the length of said sieve,
a second vertically extending channel open at both top and bottom, having substantially the same width as said first channel and placed between said sieve and said horizontal conveyor,
guide means for supporting and guiding said flexible belt along said first channel,
vertical conveyor means for vertically evacuating the objects carried by the sieve,

and means cooperating with said vertical conveyor means for applying said objects against the gripping surface of said vertical conveyor means.

5 19. The apparatus according to claim 18, wherein said fingers are fitted into regularly spaced holes of the flexible belt, the end of the fingers extending through the flexible belt being fastened thereto by means of snap rings inserted into a transversal groove of said end,

10 10 said guide means for supporting and guiding the flexible belt including a first elongated member having a longitudinal groove in which a lower part of the flexible belt is engaged, and a second elongated member in slidable contact with the belt for maintaining the engagement thereof with the first elongated member.

15 15 20. The apparatus according to claim 18, wherein the means for applying the objects against the gripping surface of the vertical conveyor comprise vertical bands having different lengths rotatably mounted on grains of pulleys having horizontal shafts, one of the pulleys having its shaft adjustable in position with respect to the gripping surface of the vertical conveyor belt.
